RIBBON ADVANCING AND REVERSING MECHANISM FOR STAMPING DEVICES, TYPEWRITERS AND THE LIKE

Hans-Ado Brandt, Munich, Germany, assignor to Agfa Aktiengesellschaft, Leverkusen, Germany

Filed Aug. 25, 1959, Ser. No. 836,021

Claims priority, application Germany Sept. 22, 1958

15 Claims. (Cl. 197—162)

The present invention relates to a ribbon advancing and reversing mechanism for use in hand stamping devices, such as date stamps, registered or insured mail stamps and the like, as well as in typewriters and other impression-producing machines.

It is already known to utilize the tension of a typewriter or like ribbon to bring about a reversal in the direction in which the ribbon is advanced. According to one such conventional construction, each of the spools which alternately take up and pay out the ribbon is connected with a ratchet wheel, and the ratchet wheels are alternately advanced in opposing directions by one of a pair of interconnected pawls, one pawl being always out of contact with its ratchet wheel while the other pawl advances the second ratchet wheel whenever a typewriter or like key is depressed. The ribbon is led through the slots of two spaced fork-shaped shifting or reversing members which are connected with each other and with the pawls by a system of levers and/or rods. The shifting members continuously deflect the ribbon in two opposing directions from a straight line and, consequently, when the ribbon is completely payed out by one of the spools and is tensioned upon subsequent depression of keys, the one or the other shifting member is caused by the tensioned ribbon to perform a movement which, over a system of cams or bevel gears, is conveyed to the respective pawl to cause the latter's movement away from the teeth of its ratchet wheel while the other pawl simultaneously engages the teeth of the second ratchet wheel. When a system of bevel gears is utilized, such gears are connected with each other by an axially movable shaft member and are moved back and forth in response to pressures generated by the tensioned ribbon upon the one or the other forked shifting member.

In hand and like stamping devices, the direction in which the ribbon advances is customarily reversed by hand. A reversing mechanism of the type presently utilized in typewriters and like machines is impractical because it occupies too much space which is not available in hand stamping devices. In addition, the known ribbon reversing mechanisms comprise a large number of component parts and, consequently, their use in hand stamping devices would greatly increase the cost of such apparatus.

An important object of the present invention is to provide a very simple and reliable ribbon advancing and reversing mechanism which is sufficiently compact to be mounted in hand stamping and like devices without unduly increasing the dimensions of such devices.

Another object of the invention is to provide an advancing and reversing mechanism for ribbons in hand stamping devices which may be installed between the spools to which the ends of the ribbon are connected.

A further object of the invention is to provide a system of braking springs which are so mounted as to prevent undesired unwinding of the ribbon from that spool which takes up the ribbon, but offer comparatively little resistance to the paying-out of the ribbon by the other spool.

2

A concomitant object of the invention is to provide a ribbon advancing and reversing mechanism which is capable of advancing the ribbon in such a way that each zone of the ribbon is subjected to equal wear and tear.

5 An additional object of the instant invention is to provide a mechanism of the above outlined characteristics in which the extent to which the ribbon is intermittently advanced may be varied within a wide range.

Still another object of the invention is to provide a 10 ribbon advancing and reversing mechanism which may be readily installed in typewriters, calculating machines, stamping devices and the like without requiring any or only slight modifications in the construction and design of such apparatus.

15 With the above objects in view, the invention resides in the provision of a ribbon advancing and reversing mechanism which, too, takes advantage of the tension in a fully payed-out ribbon to reverse the direction in which the ribbon should advance. However, instead of utilizing two individual pawls, or two sets of bevel gears, the 20 novel mechanism comprises a double pawl which is rockably mounted on an oscillatable carrier plate and whose tips or pallets are alternately movable into engagement with the teeth of two ratchet wheels connected to 25 the shafts on which the ribbon winding and unwinding spools are mounted. A very important advantage of such construction, as compared with the ribbon advancing and reversing mechanisms of known design, is in that it requires a very small number of component parts and in 30 that it occupies very little space. Thus, the entire assembly may be installed directly between the spools or reels to whose cores the ends of a ribbon are connected.

35 The carrier plate is pivoted to the frame member of a typewriter, hand stamping device or the like and is rockable between a pair of stops, the rocking movements toward and into abutment with one of the stops being caused by a constantly acting spring which is connected to the carrier plate and to the latter's frame member. It is preferred to connect the double pawl with the carrier plate by means of an eccentrically biased rocker arm which swingably supports the pawl and, in turn, is swingably connected to the carrier plate. The pawl is 40 constantly biased into engagement with the teeth of the one or the other ratchet wheel by a spring connected to the rocker arm, and the latter is constantly biased into abutment with one of two arresting members mounted on the carrier plate by another spring which is anchored in the carrier plate. The pivot axis of the double pawl is capable of performing movements in a plane substantially parallel with the line connecting the shafts on 45 which the ribbon spools are mounted.

50 Basically, the novel mechanism may operate without any specific reversing or shifting means for the pawl because the reaction force between the pawl and the ratchet wheels can be directly utilized to bring about movements of the pivot axle about which the pawl is rocked as soon as the reaction force overcomes the resistance of the aforementioned spring. The pawl-biasing spring is mounted in such a way as to constantly urge the pawl 55 into the one or the other extreme position, i.e. into engagement with the teeth of the one or the other ratchet wheel.

60 The axes about which the pawl, its rocker arm and the carrier member pivot are preferably parallel with the axis about which the ratchet wheel and the spools rotate. Also, the pawl, its rocker arm and the carrier member preferably assume the shape of plate-like bodies which move in parallel planes.

65 The novel features which are considered as characteristic for the invention are set forth in particular in the appended claims. The invention itself, however, both as to its construction and its method of operation, to

gether with additional objects and advantages thereof, will be best understood from the following description of a specific embodiment when read in connection with the accompanying drawings, in which:

Fig. 1 is front elevational view of the ribbon advancing and reversing mechanism showing the double pawl and its supports in the left-hand end position and further illustrating one form of the ribbon advancing device;

Fig. 2 is a similar view of the ribbon advancing and reversing mechanism with the pawl, its supports and the ribbon advancing device in an intermediate position;

Fig. 3 is a similar view of the mechanism with the pawl, its supports and the ribbon advancing device in the right-hand end position; and

Fig. 4 illustrates a different form of the ribbon advancing device which simultaneously serves as a means for angularly moving a printing cylinder.

The ribbon advancing and reversing mechanism is mounted on a frame member or support F forming, for example, part of a hand stamping machine or the like, preferably of the type in which the ribbon is automatically advanced when the stamping device is put to use. Such stamping devices are well known and are frequently utilized, among others, in various post offices for applying numbers to registered mail, insured mail, etc. For the sake of simplicity, Figs. 1 to 3 which will be described first show a stamping device whose ribbon is advanced by a hand-actuated lever.

The frame member or support F rotatably supports a pair of spaced parallel shafts 4, 5 for two supply spools or reels 1, 2, respectively, to whose cores are fixed the ends of a ribbon or band 3. In the position of Fig. 1, the right-hand spool 2 pays out the ribbon 3 which latter is collected by and wound onto the left-hand spool 1. It is assumed in Fig. 1 that the spools 1, 2 and the ribbon 3 are located behind the frame member F, and that each of spools 1, 2 supports an approximately equal number of ribbon convolutions 3a. The spools 1, 2 rotate with, but are separable from, their respective shafts 4, 5. The latter are rigidly connected with two ratchet wheels 6, 7 mounted thereon at the forward or front side of the frame member F. The teeth of ratchet wheel 6 cooperate with the left-hand pallet or tip 8a of a double pawl 8 which is rotatably mounted on a pivot axle 9a and is permanently biased by an eccentrically mounted coil spring 10 one end of which is connected to a stud 8c carried by the pawl 8. The other end of spring 10 is affixed to the stud 9b mounted on a plate-like rocker arm 9 which latter also carries the aforementioned pivot axle 9a on which the double pawl 8 is rotatably mounted. The rocker arm 9 is rotatably mounted on the pivot pin or axle 11a supported by a carrier or wrist plate 11, and the latter is rotatably mounted on a pivot axle 11b fixed to the frame member F and is rockable or oscillatable about member 11b between and into abutment with a pair of spaced stop pins 13, 14 mounted on the frame member F. Stop pins 13, 14 simultaneously serve as a means for limiting the rocking movements of pawl 8 in anticlockwise and clockwise directions, respectively. Thus, the positioning of pins 13, 14 determines the extent to which the ratchet wheels 6, 7 are angularly displaced by respective pallets 8a, 8b during each stroke or rocking motion of the double pawl 8. Carrier or wrist plate 11 mounts a pair of arresting pins 11d, 11e which limit the oscillatory movements of rocker arm 9 about the latter's pivot axle 11a. Double pawl 8 with its pallets 8a and 8b, the rocker arm 9, and the carrier plate 11 are disposed in parallel planes, and the pallets 8a, 8b are coplanar with the ratchet wheels 6, 7. It will be seen that the pawl 8 is rockably and eccentrically mounted with respect to the pivot axle 11a of rocker arm 9, and that the latter is rockably and eccentrically mounted with respect to the pivot axis 11b of carrier plate 11.

Member 11 carries a further stud 11c which is connected to one end of a coil spring 12; the other end of

resilient member 12 is anchored in the stud 9b which latter, as mentioned hereinbefore, also serves as a means for holding an end of the spring 10. When the carrier plate 11 abuts against the stop pin 13, studs 9b and 11c are disposed at the opposing sides of and are out of alignment with the pivot axle 11a of rocker arm 9. Thus, the spring 10 tends to pivot the pawl 8 in anticlockwise direction about the pivot 9a, and the spring 12 simultaneously tends to rock the arm 10 in anticlockwise direction into abutment with the arresting pin 11e. A third coil spring 15, connected to the stud 11c and to a stud 15a carried by the frame or support member F, constantly urges the carrier plate 11 into abutment with the stop pin 14. The pivot axes 9a, 11a and 11b are parallel with the axes of shafts 4 and 5.

When the stamping device of which the frame member F forms a component part is put to use, the carrier plate 11 is caused to rock about its pivot 11b from the position of Fig. 3 into the position of Fig. 1, i.e. into abutment with the stop pin 13. The lever 23, articulately connected to the carrier plate 11 by a rivet 24, constitutes one form of means for rocking the member 11 against the action of spring 15. The free end of this lever carries a pin 25 which abuts against and is slidable along a flange Fa of the frame member F. The means for rocking the lever 23 and the carrier 11 against the action of the coil spring 15 comprises a handgrip member 26 fixed to the free end of the lever and adapted to be grasped by the fingers of an operator to advance the lever in a direction to the left, i.e. from the position of Fig. 3 into that shown in Fig. 1, whereby the carrier 11 moves from the right-hand stop pin 14 into abutment with the other stop pin 13. Upon release of the handgrip member 26, the spring 15 immediately returns the carrier 11 into the position of Fig. 3. During the movement of carrier plate 11 to the left, i.e. in anticlockwise direction, the pallet 8a of double pawl 8 engages with a selected tooth of the ratchet wheel 6 and rotates the latter in anticlockwise direction to wind the ribbon 3 onto the spool 1. The magnitude of the angular movement performed by the spool 1 under the influence of pawl 8 corresponds to the width of more than a single tooth on ratchet wheel 6, i.e. the length of ribbon 3 payed out by the right-hand spool 2 corresponds to a multiple of that unit length which would be payed out were the ratchet wheel rotated only a distance corresponding to the width of a single tooth thereof. When the spring 15 rocks the carrier plate 11 with members 8, 9 in clockwise direction, a resilient member in the form of a braking spring 16 prevents unwinding of the ribbon 3 from the left-hand spool 1. Thus, and as shown in Fig. 1, the braking spring 16 must resist the tendency of shaft 4 to rotate in clockwise direction under the influence of the coil spring 10 which latter tends to urge the left-hand pallet 8a into firm engagement with the teeth of ratchet wheel 6.

The brake spring 16 preferably assumes the shape of a spiral loop spring, also known as a spring band brake; its purpose is to brake the spool 1 only in a direction to prevent unwinding of the band 3 therefrom. The member 16 consists of a length of resilient material, such as a metallic band or wire, which is wound spirally and under initial tension onto the shaft 4. Due to such mounting, the braking action of the spring 16 in the direction of its convolutions (clockwise in Figs. 1 to 3) is much greater than in the opposing (anticlockwise) direction. Thus, when the spool 2 rotates clockwise to wind the ribbon 3 thereon, the spring 16 offers considerable resistance to such movement and maintains the ribbon under tension. On the other hand, when the ribbon is payed out by the spool 2 and is wound onto the left-hand spool 1 in anticlockwise direction, the brake spring 16 offers comparatively little resistance to such movement. This is due to the fact that a clockwise rotation of the shaft 4 tends to tighten the convolutions

of the spring 16 thereon whereas an anticlockwise rotation of the shaft 4 tends to unwind the spring and thus reduces its braking action. This brake spring simultaneously maintains the ribbon 3 under requisite tension and, as above stated, also prevents the pawl 8 from moving the ratchet wheel 6 in clockwise direction when the pawl is moved to the right by the coil spring 15. On the other hand, the resistance met by the pawl 8 in causing angular movements of the ratchet wheel 6 and spool 1 in anticlockwise direction is rather small because the braking action of spring 16 is felt solely in clockwise direction.

It will be readily understood that the lever 23 which acts upon and rocks the carrier plate 11 toward the stop pin 13 need not necessarily move the carrier plate all the way into abutment with the member 13. Thus, if the carrier plate 11 is moved toward but not entirely into actual abutment with the stop pin 13, the pallet 8a will rotate the ratchet wheel 6 through a smaller angle. Consequently, by controlling the extent to which the carrier plate 11 is rocked, the extent of consecutive movements performed by the ribbon 3 in the direction toward the reel 1 may be changed as desired. As soon as the stud 11c or another part connected to member 11 is released, spring 15 immediately returns the carrier plate into abutment with the stop pin 14.

When the ribbon 3 is payed out by the right-hand spool 2, the ratchet wheel 6 is prevented from continuing its angular movements in anticlockwise direction, i.e. in the direction to wind the ribbon 3 onto the spool 1. During the subsequent stroke of rocker arm 11 into abutment with the left-hand stop pin 13, the pallet 8a of pawl 8 meets a substantial resistance, thus causing the pawl to pivot about member 9a in clockwise direction against the resistance of spring 10 and simultaneously causing the rocker arm 9 to pivot about its axle 11a in clockwise direction against the action of coil spring 12. Such position of the rocker arm 9 is shown in Fig. 2. It will be noted that the tension to which spring 10 subjects the pawl 8 is smallest when the pawl 8 and rocker arm 9 assume the position of Fig. 2, i.e. the stud 8c is then closer to the stud 9b than in the positions of Figs. 1 and 3.

As the carrier plate 11 continues its advance toward the left-hand stop pin 13, the rocker arm 9 suddenly snaps over under the influence of spring 12 to move into abutment with the right-hand arresting pin 11d as is shown in Fig. 3. The stud 9b is then moved in clockwise direction about its pivot axle 11a and, consequently, the resilient element 10 acting between studs 8c and 9b now urges the right-hand pallet 8b of double pawl 8 into engagement with the teeth of ratchet wheel 7. Thus, the movements of carrier plate 11 into abutment with the stop pin 14, after the carrier plate is acted upon by the lever 23 and returned by spring 15 into abutment with member 14, bring about angular movements of ratchet wheel 7 in clockwise direction to wind the ribbon 3 onto the right-hand spool 2. Such angular movements of ratchet wheel 7 under the influence of spring 15 continue until the ribbon 3 is completely payed out by the spool 1, whereupon the ratchet wheel 7 resists further rotation by the pallet 8b and the rocker arm 9 caused to snap over the intermediate position of Fig. 2 back into the position of Fig. 1. Thus, the tension of ribbon 3 causes the spring 12 to rock the arm 9 between the arresting pins 11d, 11e and the resilient member 10 thereupon alternately urges pallets 8a, 8b into engagement with the teeth of ratchet wheels 6, 7, respectively. The pivot axle 9a of double pawl 8 travels with respect to the carrier plate 11 in a path which is substantially parallel with the line connecting the axes of shafts 4 and 5. The springs 10, 12 alternately bias members 8, 9 in anticlockwise and clockwise directions, depending upon whether the pallet 8a engages with the teeth of ratchet wheel 6 or

the other pallet 8b engages with the teeth of ratchet wheel 7.

It will be noted that, to move the rocker arm 9 from the position of Fig. 1 into that of Fig. 3, an outside force is required only to such an extent as to rock the member 9 from the position of Fig. 1 or 3 into that of Fig. 2 while the second half of rocking movement performed by the rocker arm 9 occurs under the influence of spring 12. This spring resists angular movements of rocker arm 9 about its pivot 11a until the latter is aligned with studs 9b and 11c, and thereupon assists the advance of rocker arm 11 into one of its end positions of abutment with arresting pin 11d or 11e. The action of spring 10 upon the pawl 8 is somewhat different because the pivot axle 9a is not located between the studs 8c and 9b. Thus, resilient element 10 constantly tends to align the studs 8c, 9b with the pivot axle 9a, and therefore permanently urges the pallet 8a or 8b into engagement with the teeth of ratchet wheel 6 or 7, respectively.

Whether the spring 10 urges pallet 8a into engagement with ratchet wheel 6 or the pallet 8b into engagement with ratchet wheel 7 depends upon the position of rocker arm 9.

The magnitude of the angle through which the ratchet wheels 6, 7 are advanced by the pawl 8 during each movement of the handgrip means 26 in a direction to the left must be sufficient to insure that the rocker arm 9 snaps over when the ribbon 3 is under tension. In fact, the advance of the ribbon is actually excessive and, consequently, it could happen that only certain isolated zones of the ribbon would be used and that only such isolated ribbon zones would be put to repeated use. Upon several reversals in the direction in which the ribbon 3 advances, certain zones of the latter would become worn out while the zones therebetween would remain intact, i.e., such use of the ribbon would be very uneconomical. This is avoided by so positioning the stop pins 13, 14 that each movement of the carrier plate 11 thereagainst preferably brings about an angular movement of ratchet wheels 6, 7 equaling the width of three and one-half teeth thereon. In such manner, the pallets 8a, 8b advance the ribbon while continuously engaging with different teeth of ratchet wheels 6, 7, respectively. It can be readily calculated that such positioning of the stop pins 13, 14 causes the pallets 8a, 8b to engage three different teeth on each of ratchet wheels 6, 7 during six subsequent reversals of the direction in which the ribbon 3 advances. This is due to the fact that, before the direction of the ribbon 3 is reversed, the ribbon is not fully payed out by the spool 1 or 2 but that there remains convoluted on the respective spool a length of ribbon corresponding to the angular movement of ratchet wheel 6 or 7 a distance equal to the width of one or two teeth thereon. During the subsequent stroke of pawl 8, the ribbon is fully payed out by the respective spool and, in addition, the rocker arm 9 is moved partially away from its arresting pin 11d or 11e, this being due to the fact that, as above described, the advance of the ratchet wheels 6, 7 during each stroke of double pawl 8 preferably corresponds to the width of three and one-half teeth thereon. During the subsequent stroke of pawl 8, the rocker arm 9 is completely swung over the intermediate position of Fig. 2 into that shown in Fig. 1 or Fig. 3. Thus, the snapping-over or rocking of arm 9 is brought about during two successive strokes of the pawl 8 in response to two successive movements of carrier plate 11 into abutment with the stop pin 13 or 14.

The right-hand shaft 5 is braked by a second spiral spring 17 in a manner analogous to that of the aforementioned braking spring 16. Resilient members 16, 17 are not connected directly with the frame member F but are formed with resilient extensions or stems 16a, 17a, respectively, whose free ends form elongated loops or nooses slidably mounted on a pair of pins or studs 18, 19, respectively, which are fixed to the frame member F. When the double pawl 8 performs one of its strokes,

the comparatively long stem of that braking spring which controls the unwinding spool is slightly bent or arched to exert a moment of rotation or torque upon the respective shaft to in such a manner maintain the ribbon 3 under requisite tension. While the pawl 8 moves between the ratchet wheels 6 and 7, e.g. when the pallet 8b moves away from its ratchet wheel 7, the long stem 16a of resilient member 16 maintains the ribbon under uniform tension. This is due to the fact that the stem 16a is slightly arched or bent while it resists unwinding of the ribbon off the spool 1. The formation of a loop at the free end of stem 16a allows for such deformation. The ribbon 3 communicates the tension to the stem 17a of the other brake spring 17 when the pawl 8 moves from the ratchet wheel 6 toward the other ratchet wheel 7.

The ribbon advancing mechanisms of presently known design utilize braking springs whose action upon the spools is of equal magnitude regardless of whether the ribbon is wound onto or payed out by the spools. Thus, the ribbon advancing mechanism must overcome substantial resistance of braking springs in order to cause the ribbon to advance from the one to the other spool. In contrast to such construction, the springs 16, 17 act as one-way braking means in that they resist unwinding of ribbon 3 from respective spools 1, 2 with a considerable force but offer comparatively little resistance to the winding of the ribbon onto said spools. Consequently, the advance of ribbon 3 toward the spool 1 or 2 against the force of spring 16 or 17 requires a smaller force than in similar mechanisms of known design.

At its upper end, the frame member F is formed with an extension 20 carrying a pair of deflecting or guide rollers 21, 22 for the ribbon 3. The purpose of these parts will now be described in greater detail with reference to Fig. 4 which illustrates a different ribbon advancing device mounted at that side of the frame member F which is turned away from the ribbon reversing mechanism of Figs. 1 to 3, i.e. at the side which is adjacent to the spools 1 and 2. The frame member F rotatably supports a pin or pivot axle 27 which carries a coaxial sleeve 28 connected with a substantially radial advancing arm 29 and with a radial bracket 30. The sleeve 28 rotatably supports a coaxial printing cylinder or drum 31 whose periphery may carry a series of symbols, e.g. numerals, such as are utilized in date, hour or serial number stamps. Whenever the advancing arm 29 is swung in clockwise direction, a non-represented mechanism of any known design advances the cylinder 31 through a given angle in order to move a different symbol, e.g. a numeral, a letter, a series of numerals and/or a series of letters, into a position adjacent to the ribbon 3 intermediate the deflecting rollers 21 and 22. A sheet of paper or any other material 32 on which an impression is to be imprinted is placed adjacent to the other side of the ribbon.

The flange Fa of the frame member F carries a bracket 33 which supports an electromagnet 34 in a position of alignment with the sheet 32 and with the uppermost character or numerals on the printing cylinder 31. The core 35 of electromagnet 34 carries at its lower end an impression plate 36 which, when the electromagnet 34 is energized and its core 35 moved in downward direction, strikes against the sheet 32 and moves the same against the ribbon 3 and the selected character or number on the cylinder 31 to produce a desired impression.

The stud 11c extends through an arcuate closed slot 37 formed in the frame member F into the path of the aforementioned bracket 30. Thus, whenever the advancing arm 29 is rocked to turn the printing cylinder, the bracket 30 simultaneously swings the carrier plate 11 against the action of the spring 15 by acting upon the stud 11c. The handgrip member 26 then merely constitutes an alternate means for advancing the ribbon 3 when a series of identical impressions is to be imprinted

on the sheet 32, i.e. when the angular position of the printing cylinder 31 remains unchanged during a series of consecutive energizations of the electromagnet 34.

It will be noted that the major part of the ribbon advancing and reversing mechanism is installed directly between the spools 1 and 2; thus, the entire mechanism occupies very little space and, in fact, does not increase the dimensions of the stamping device since it is practically inevitable that a space be formed intermediate the spools 1 and 2 because the ribbon must be flattened out between the spools a distance sufficient to permit the forming of impressions over a required area. For example, in the embodiment shown in Figs. 1 to 3, the ribbon 3 may form impressions anywhere between the deflecting rollers 21 and 22. Thus, the space between the spools 1, 2 occupied by the ribbon advancing and reversing mechanism of my invention is not provided with a view to accommodate the novel assembly but is rather due to the necessity to provide for a flat length of ribbon 3 (between the rollers 21, 22) which forms impressions upon contact with the type and the surface to be imprinted. If the mechanism of Figs. 1 to 3 were installed in a typewriter or calculating machine, the spools 1 and 2 could be placed much closer to each other than in the presently utilized machines since the space between ratchet wheels 6, 7 must exceed only slightly the width of carrier plate 11.

Without further analysis, the foregoing will so fully reveal the gist of the present invention that others can, by applying current knowledge, readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

What is claimed as new and desired to be secured by Letters Patent is:

1. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a double pawl having two pallets; means rockably mounting the pawl on said carrier means for movements in a plane substantially parallel with the line connecting said shafts; stop means fixed to said support means for limiting the rocking movements of said carrier means and for simultaneously limiting the rocking movements of said pawl between a pair of end positions in which one pallet engages with one of said ratchet wheels and the other pallet engages with the other ratchet wheel, respectively; eccentrically mounted resilient means for alternately biasing said pawl into one of said end positions; and a ribbon having ends connected to said spools and adapted to prevent rotation of said ratchet wheels by the respective pallets when one spool fully pays out the ribbon whereby the pawl is rocked against the action of said resilient means.

2. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; means rockably mounting the pawl on said rocker arm for movements in a plane substantially parallel with the line connecting said shafts between a pair of end positions in which one pallet engages with one of said ratchet wheels and the other pallet engages with the other ratchet wheel, respectively; eccentrically mounted first resilient means for alternately biasing said pawl into one of said end positions; eccentrically mounted second resilient means operating between said carrier means and

said rocker arm for constantly biasing the latter into a pair of spaced end positions with respect to said carrier means together with said pawl; and a ribbon having ends connected to said spools and adapted to prevent rotation of said ratchet wheels by the respective pallets when one spool fully pays out the ribbon whereby the pawl is rocked against the action of said first resilient means with respect to said rocker arm and the latter is pivoted with respect to said carrier means and against the action of said second resilient means.

3. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between and about an axis parallel with said shafts; a rocker arm pivotably mounted on said carrier means about an axis parallel with said shafts; a double pawl having two pallets; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

4. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between and about an axis parallel with said shafts; a rocker arm pivotably mounted on said carrier means about an axis parallel with said shafts; a double pawl having two pallets; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions over a median position in which said resilient means biases the pawl to an extent less than in each of said end positions; second eccentric resilient means operating between said rocker arm and said carrier means for alternately biasing the rocker arm into a pair of spaced end positions with respect to said carrier means together with said pawl; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

5. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between and about an axis parallel with said shafts; a rocker arm pivotably mounted on said carrier

means about an axis parallel with said shafts; a double pawl having two pallets; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions by rocking the pawl about said pivot means in clockwise and counterclockwise directions, respectively; second eccentric resilient means operating between said rocker arm and said carrier means for alternately biasing the rocker arm into a pair of spaced end positions with respect to said carrier means together with said pawl; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

25 6. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between and about an axis parallel with said shafts; a rocker arm pivotably mounted on said carrier means about an axis parallel with said shafts; a double pawl having two pallets; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl onto one of said end positions; second eccentric resilient means operating between said rocker arm and said carrier means for alternately biasing the rocker arm into a pair of spaced end positions with respect to said carrier means together with said pawl; stud means mounted on said rocker arm and connected with one end of said first and said second resilient means; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

30 7. A ribbon advancing and reversing mechanism comprising, in combination: support means; a pair of spaced parallel shafts rotatably mounted on said support means; a spool and a ratchet wheel fixed for rotation to each shaft; a carrier plate rockably mounted on the support means between and about an axis parallel with said shafts; a plate-like rocker arm parallel with and pivotably mounted on said carrier plate about an axis parallel with said shafts; a plate-like double pawl having two pallets and parallel with said rocker arm; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier plate for alternately biasing the

rocker arm into a pair of spaced end positions with respect to said carrier plate together with said pawl; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier plate against the action of said first and second resilient means, respectively, when the carrier plate is rocked with respect to said support means.

8. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between and about an axis parallel with said shafts; a rocker arm pivotably mounted on said carrier means about an axis parallel with said shafts; a double pawl having two pallets; pivot means rockably mounting said pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a pair of stop pins connected to the support means for limiting the rocking movements of said carrier means; a spring connected to the support means and to said carrier means for constantly biasing the latter into abutment with one of said stop pins; and a ribbon having ends connected to said spools and adapted to prevent rotation of said ratchet wheels by respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

9. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; pivot means rockably mounting said pawl on said rocker arm for movements between a pair of end positions in which one pallet engages with one of said wheels and the other pallet engages with the other wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a pair of stop pins connected to the support means for limiting the rocking movements of said carrier means, said pawl abutting against one of said stop pins in each of its end positions; a spring connected to said support means and to said carrier means for constantly biasing the latter into abutment with one of said stop pins; and a ribbon having ends connected to said spools and adapted to prevent rotation of said ratchet wheels by the respective pallets when one spool fully pays out the ribbon, whereby the pawl is rocked about said pivot means and the rocker arm is pivoted with respect to said carrier means against the action of said first and second resilient means, respectively, when the carrier means is rocked with respect to said support means.

10. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; pivot means rockably mounting said pawl on said rocker arm for movements between a pair of end positions in which one pallet engages with one of said wheels and the other pallet engages with the other wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a pair of arresting pins mounted on said carrier means for limiting the rocking movements of said rocker arm in two opposing directions, the rocker arm abutting against one of said arresting pins in each of said last mentioned end positions; a pair of stop pins connected to the support means for limiting the rocking movements of said carrier means, said pawl abutting against one of said stop pins in each of its end positions; a spring connected to said support means and to said carrier means for constantly biasing the latter into abutment with one of said stop pins; and a ribbon having ends connected to said spools and adapted to prevent rotation of said ratchet wheels by the respective pallets when one spool fully pays out the ribbon whereby the pawl is rocked about said pivot means and the rocker arm is pivoted with respect to said carrier means against the action of said first and second resilient means, respectively, when the carrier means is rocked with respect to said support means.

11. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; pivot means rockably mounting said pawl on said rocker arm for movements between a pair of end positions in which one pallet engages with one of said wheels and the other pallet engages with the other wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a pair of stop pins connected to the support means for limiting the rocking movements of said carrier means, said pawl abutting against one of said stop pins in each of its end positions; a spring connected to said support means and to said carrier means for constantly biasing the latter into abutment with one of said stop pins; and a ribbon having ends connected to said spools and adapted to prevent rotation of said ratchet wheels by the respective pallets when one spool fully pays out the ribbon whereby the pawl is rocked about said pivot means and the rocker arm is pivoted with respect to said carrier means against the action of said first and second resilient means, respectively, when the carrier means is rocked with respect to the support means; and a braking spring operatively connected to each of said shafts and anchored in said support means for preventing unwinding of the ribbon off the respective spool when the pawl is idle.

12. A ribbon advancing and reversing mechanism comprising, in combination: support means; a pair of

spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; pivot means rockably mounting the pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a ribbon having ends connected to said spools and adapted to prevent rotation of said ratchet wheels by the respective pallets when one spool pays out the ribbon whereby the pawl is rocked about said pivot means and the rocker arm is pivoted with respect to said carrier means against the action of said first and second resilient means, respectively, when the carrier means is rocked with respect to the support means; a braking spring connected to each of said shafts for preventing unwinding of the ribbon off the respective spool when the pawl is idle, each braking spring having a stem and a loop at the end of the stem; and a pair of pins, each connected to said support means and each received in one of said loops for anchoring the respective braking spring to said support means.

13. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a rocker arm pivotably mounted on said carrier means; a double pawl having two pallets; pivot means rockably mounting the pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a ribbon having ends connected to said spools and adapted to prevent rotation of said ratchet wheels by the respective pallets when one spool pays out the ribbon whereby the pawl is rocked about said pivot means and the rocker arm is pivoted with respect to said carrier means against the action of said first and second resilient means, respectively, when the carrier means is rocked with respect to the support means; a braking spring connected to each of said shafts for preventing unwinding of the ribbon off the respective spool when the pawl is idle, each braking spring having a plurality of convolutions wound about the respective shaft and a stem formed with a loop at one end thereof; and a pair of pins, each connected to said support means and each received in one of said loops for anchoring the respective braking spring to said support means.

14. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; means connected to the carrier means for rocking same; a rocker arm pivotably mounted on said carrier means; a double pawl

having two pallets; pivot means rockably mounting the pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a ribbon having ends connected to said spools and adapted to prevent rotation of said ratchet wheels by the respective pallets when one spool pays out the ribbon whereby the pawl is rocked about said pivot means and the rocker arm is pivoted with respect to said carrier means against the action of said first and second resilient means, respectively, when the carrier means is rocked with respect to the support means; a braking spring connected to each of said shafts for preventing unwinding of the ribbon off the respective spool when the pawl is idle, each braking spring having a stem and a loop at the end of the stem; and a pair of pins, each connected to said support means and each received in one of said loops for anchoring the respective braking spring to said support means.

15. A ribbon advancing and reversing mechanism comprising, in combination: support means; a pair of spaced parallel shafts rotatably mounted on said support means; a spool and a ratchet wheel fixed for rotation to each shaft; carrier means rockably mounted on the support means between said shafts; a pair of stop pins connected to the support means for limiting the movements of said carrier means in two opposing directions; a spring connected to said support means and to said carrier means for constantly biasing the latter into abutment with one of said stop pins; means for rocking the carrier means against the action of said spring in a direction toward the other stop pin; a rocker arm pivotably mounted on said carrier means; a double pawl having two pallets; pivot means mounting the pawl on said rocker arm for movements in a plane substantially parallel with the line connecting said shafts between a pair of end positions in which one pallet engages with one of said ratchet wheels and the other pallet engages with the other ratchet wheel, respectively; first eccentric resilient means operating between said pawl and the rocker arm for alternately biasing the pawl into one of said end positions; second eccentric resilient means operating between said rocker arm and said carrier means for alternately biasing the rocker arm into a pair of spaced end positions with respect to said carrier means together with said pawl; a ribbon having ends connected to said spools and adapted to prevent rotation of said ratchet wheels by the respective pallets when one spool pays out the ribbon whereby the pawl is rocked about said pivot means and the rocker arm is pivoted with respect to said carrier means against the action of said first and second resilient means, respectively, when the carrier means is rocked with respect to the support means; a braking spring connected to each of said shafts for preventing unwinding of the ribbon off the respective spool when the pawl is idle, each braking spring having a stem and a loop at the end of the stem; and a pair of pins, each connected to said support means and each received in one of said loops for anchoring the respective braking spring to said support means.
